UNITED STATES PATENT OFFICE

ADOLF WASCHNACK, OF NEU-FINKENKRUG, NEAR BERLIN, GERMANY, ASSIGNOR TO SIEMENS & HALSKE AKTIENGESELLSCHAFT, OF SIEMENSSTADT, NEAR BERLIN, GERMANY

TELEPHONE SYSTEM

Application filed September 12, 1931, Serial No. 562,478, and in Austria August 23, 1930.

The present invention relates to a circuit arrangement for telephone systems having a plurality of exchanges and relates in particular to such systems in which an existing connection is to be switched over to another subscriber. There are already arrangements known in which the switching over of the connection is effected by a speaking station calling an operator of his own exchange, requesting this operator to set up a new connecting route to the second speaking station. These arrangements have the disadvantage that the switching over of the connection cannot take place with the required speed when the operator is busy setting up other connections. On the other hand, these arrangements require comparatively complicated devices which, particularly in small systems, have to be considered for the sake of economy. The object of the present invention is to set up connections with greater speed and using a small number of auxiliary devices as possible, this being achieved by switching means being provided which, under the influence of a special switching operation at the speaking station calling a second subscriber of its own exchange, cause the switching over of the connection to the called second subscriber. The arrangement according to the invention offers important advantages particularly in cases concerning exchanges which periodically lack the services of an operator, for example, at night, or the operator being busy setting up other connections. It is also of advantage in substation systems where exchange lines are switched through to certain speaking stations associated with the substation system at certain periods or in cases where the services of a special operator is not available such as, for example, a speaking station associated with a substation system in which all incoming exchange calls are received and switched over to the required subscriber.

In the first mentioned case various devices have been suggested in which, for example, a small auxiliary exchange is installed at the stations to which incoming junction lines are switched through at certain periods (at

night) and over which only preferred exchanges can be reached. It is only to be expected that these devices, similarly to those suggested for automatic systems so-called toll control positions are comparatively complicated and, in addition, completely prevent a certain number of speaking stations from receiving any incoming connections. All these disadvantages are eliminated by the present invention.

According to one feature of the invention, part of the connecting devices of an exchange which are used for speaking connections or local calls are used in the setting route and part in the speaking route in the case of calls incoming from another exchange.

According to another feature of the invention, in the setting up of a connection to another exchange, a line outgoing in this direction is connected in the calling exchange to a line which is utilized to set up internal connections.

A still further feature of the invention relates to a telephone system having a plurality of exchanges in which the calls arriving from other exchanges are received by a speaking station and transferred to the required speaking station. This is accomplished by the speaking station which receives the calls from other exchanges bringing about the setting of the connecting device (AS) used for its connection to the calling line, to the required speaking station.

Referring now to the drawings comprising Figs. 1-4, they show by means of the usual circuit diagrams a sufficient amount of apparatus in a telephone system embodying the features of the invention to enable the same to be understood.

Fig. 1 shows a sub-exchange comprising a call finder AS arranged to find the calling subscriber's line and a final selector LW over which local connections are established. Trunk connections to another exchange are made over trunk line ZA.

Fig. 2 shows a modification of the system shown in Fig. 1 in that the outgoing connections are made over switches of an automatic private exchange while incoming connections are set up by an operator.

Fig. 3 shows a modified circuit for the release relay N.

Fig. 4 shows a modification of the portion of the circuit of Fig. 2, which controls the setting up of inquiry connections.

1. Setting up an internal connection

If, for example, subscriber N1 wishes to set up a connection with any subscriber of his own exchange, the following circuit is set up when he lifts his receiver: earth, contact 1t over the subscriber's line loop, resistance Wi1, contact 2t, c-wiper of the final selector LW in zero position, winding I of relay V, battery, earth. Relay V is energized in this circuit and by the closing of contact 3v effects the connecting up of the rotary magnet DAS of the call finder AS over: earth, relay interrupter RU, contacts 25t, 3v, 5s, rotary magnet DAS, battery, earth. The call finder AS is advanced by means of the rotary magnet until the following circuit for winding I of relay S has been set up: earth, contact 1t over subscriber's line loop, b-wiper of the call finder AS, contacts 6t, 7r, winding I of relay S, battery, earth. By means of relay S, now energized, the rotary magnet DAS of the call finder AS is brought to rest by opening contact 5s. By the closing of contact 8s the relays T1 to T4 are energized over: earth, contact 8s, relays T1 to T4, battery, earth. Relays T1 to T4 actuate all the t-contacts whereby the calling circuits (circuit of relay V) of all the subscribers, for example, subscribers N, N1, N2 are broken at contacts 1t, 2t, 9t and 10t. The device for all the other subscribers is hereby guarded.

Upon the energization of relays T1 to T4 the relay V is energized over: earth, winding III of relay S, contact 17t, c-wiper of the final selector LW in zero position, winding I of relay V, battery, earth.

The feeding circuit for the calling subscriber N1 now extends over: earth, contact 11t, winding II of relay S, contact 12r, winding II of relay X, a-wiper of the call finder AS to subscriber N1, b-wiper of the call finder AS, winding I of relay X, contact 7r, winding I of relay S, battery, earth.

The subscriber now sends out the impulses for the setting of the final selector LW2. According to these impulses relay S is disconnected from battery and actuates the rotary magnet DLW of the final selector in the following circuit: earth, contacts 13h^{II}, 14t, 15s, winding II of relay V, contact 16v, rotary magnet DLW of the final selector LW, battery, earth. The final selector LW is now set to the required contact. Relay V remains energized in the circuit for the rotary magnet only during the impulse series but releases after this impulse series, as the circuit for winding I of relay V is broken by the advance of the switch wiper c associated with the final

selector LW. The required subscriber is called in the following circuit: earth contact 11t, winding II of relay S, contact 12r, winding II of relay X, contact 18p, a-wiper of the final selector LW to required subscriber, b-wiper of the final selector LW, contact 19u, winding I of relay U, contact 20v over the contact which closes every four seconds, ringing current source of supply RQ.

When the required subscriber answers, the relay U is connected to battery over the four-second contact being set in its normal position and resistance Wi3. By the opening of contact 19u, effected by relay U, as well as by the closing of contact 21u the speaking leads are connected up and the ringing current is broken. Relay U remains energized over winding II in the following circuit: earth, contact 22t, winding II of relay U, contact 23u, contact 24v, rotary magnet DLW of the final selector LW, battery, earth. The rotary magnet DLW does not operate in this circuit. The speaking connection between the calling and the required subscriber is thus set up.

The established connection is released in the following manner: If either the calling or the called party replaces the receivers, relay S is disconnected from the battery and by the opening of contact 8s causes the release of relays T1 to T4. Hereby all the t-contacts are restored to their normal positions. By the closing of contact 25t the following circuit for the rotary magnet DLW of the final selector is set up: earth, relay interrupter RU, contact 25t, c-wiper of the final selector LW in position 1—10, rotary magnet DLW of the final selector, battery, earth. The rotary magnet DLW operates until the final selector LW has reached its zero position and thereby broken the above described circuit. The locking circuit for relay U is broken at contact 22t. All the switching means are now restored to normal and the device can be used for a fresh connection.

2. Setting up an exchange connection

If, for example, subscriber N1 wishes to set up a connection with the exchange, the setting of the call finder AS to the calling subscriber is effected in the same manner as described in the above. When the call finder has been set as required, the subscriber N1 momentarily presses key T whereby the differential relay X in the feeding circuit is energized in known manner. Relay P is hereby energized in the following circuit: earth, contacts 26t, 27r, 29x, 32p, winding II of relay P, battery, earth. Relay P is energized and sets up an energizing circuit for relay H over its contact 30p as follows: earth, contacts 26t, 27r, 29x, 30p, winding I of relay H, battery, earth. Relay H is a two step relay energized in the first and second stage in the last described circuit.

It should be noted that relay H actuates all contacts denoted by I in the first, all contacts denoted by II in the second and all contacts denoted by I and II in the first and 5 second stages.

By the closing of contact $31h^{II}$ a locking circuit for relays P and H is set up over: earth, contacts $26t$, $27r$, winding II of relay H, winding I of relay P, contacts $31h^{II}$, $30p$, 10 winding I of relay H, battery, earth. The switching over the line connecting the call 15 finder AS and final selector LW to the exchange lead zA is effected by a relay P opening the contacts $34p$ and $18p$ and closing contacts $35p$ and $36p$. The exchange is called by the operation of relay H.

After the setting of the call finder AS, the relay S, as already described, is energized, and relays X, P and H likewise energize by 20 the momentary depression of the key T1. By the operation of relays S and H, a bridge is set up between the exchange line over contacts $37s$, $38h^I$, and relay Dr, said bridge causing relay Dr in addition to the call finder 25 in the exchange to be energized. The exchange line is switched through at contacts $39dr$ and $40dr$ by this relay Dr.

The setting of the switches in the exchange is effected in known manner by the feeding 30 bridge relay S, in which case the contact $37s$ is the impulse contact. After the switches in the exchange have been properly set the two subscribers can converse with each other.

3. Setting up of an enquiry connection during an exchange conversation

If the subscriber wishes to speak to another subscriber associated with a sub-ex- 40 change during the exchange conversation, he again presses momentarily the key T1, thereby energizing the differential relay X. By the opening of contact $33x$ and the closing of contact $29x$, the winding I of relay P and 45 winding II of relay H are short-circuited. Relay P releases and opens at contact $30p$ the locking circuit for relay H over winding II of relay H. This relay H is maintained energized over: earth, contact $26t$, resistance $W\frac{1}{4}$, contact $55h^I$ and II, winding I of relay H, battery, earth, but when energized in the 50 above circuit actuates only the contacts in the first state, that is to say those of the h-contacts denoted by I or I and II, respectively.

55 By the opening of contacts $35p$ and $36p$ and the closing of contacts $18p$ and $34p$, the calling subscriber is switched over to the line leading to the final selector LW and can, therefore, as already described, set up a connection with any subscriber associated with the substation. During the enquiry connection the locking bridge between the exchange line is maintained over contacts $37s$, $38h^I$, choke Dr.

60 65 If the calling subscriber N1 after the en-

quiry connection has been effected wishes to use the exchange line again, the switching over is effected in the following manner. Relay X is re-energized by a momentary pressing of the key and connects up winding II of relay P by the closing of contact $29x$. Relay P, as already described, is connected up to the exchange line and energizes relay H in the second stage. The rotary magnet DLW of the final selector LW receives impulses from the relay interrupter RU over: earth, relay interrupter, contacts $56x$, $57h^{II}$, d-wiper of the final selector in position 1—10, rotary magnet DLW, battery, earth, until the final selector LW has reached its zero position and thereby broken the last described circuit.

If, on the other hand, subscriber N1 would wish to hand over the exchange connection to the subscriber with whom he has had an enquiry connection, the subscriber N1 must 70 press the key T1 a longer period than heretofore. Relay X is thereby energized accordingly, with the consequence that the thermo relay TH is energized over contact $41x$, thereby causing contact $42th$ to close. A circuit 75 for relay R is set up over: earth, contacts $41x$, $42th$, relay R battery, earth. By the closing of contact $48r$, after relay S has released by the opening of contacts $12r$ and $7r$, the relay R is maintained energized over: 80 earth, contacts $44t$, $43r$, $45s$, relay R, battery, earth. The relays T1 to T4 are maintained 85 energized over contact $49r$ at the release of relay S which causes contact $8s$ to be opened, the exchange connection being maintained 90 independent of contacts $37s$ over contact $53h^{II}$.

The following circuit for the rotary magnet DAS of the call finder is set up at contact $46r$: earth, relay interrupter RU, contacts $46r$, $5s$, rotary magnet DAS of call 95 finder AS, battery, earth. The rotary magnet DAS actuates the call finder AS, until the following circuit for relay S has been established over winding I: earth, battery, winding I of relay S, contact $47r$, c-wiper of the call finder AS in the position of the enquiry subscriber (for example 3), c-wiper of the final selector LW, likewise in the position of the enquiry subscriber 3, over line 48, contact $17t$, winding III of relay S, earth. The 100 circuit for the rotary magnet DAS of the call finder AS is broken by the opening of contact $5s$. The call finder is thus set to the subscriber with whom the subscriber N1 has had an enquiry connection. By the closing of contact $54s$, relay P is energized over: earth, contacts $26t$, $28r$, $54s$, $33x$, $32p$, winding II of relay P, battery, earth. The switching over to the exchange line at contacts $35p$ and $36p$ now takes place while relay H is energized in the second stage by the closing of contact $30p$. A locking circuit for relays P and H is set up over contact $31h^{II}$ when relay R releases after the opening of the circuit for this relay R at contact $45s$.

The locking circuit for relays P and H then extends over: earth, contacts 26t, 27r, winding II of relay H, winding I of relay P contacts 31h^{II}, 30p, winding I of relay H, battery earth. If the subscriber with whom an enquiry connection has been set up is switched over to the exchange line, the release of the final selector is effected in the following manner: On the energization of relay P, 10 the relay H is energized in the second stage as already mentioned. When the final selector is properly set, the rotary magnet DLW is actuated until the final selector has reached its zero position over the following 15 circuit: earth, relay interrupter RU, contacts 56az and 57h^{II}, d-wiper of the final selector in position 1—10, rotary magnet, battery, earth.

20 *4. Incoming exchange connections.*

If a call arrives from the exchange, the calling device AZ, for example, a bell, is operated in the usual manner by the ringing current issued from the exchange. This calling 25 device AZ is located in the subscriber's N room which is provided for the connections of the exchange operations. By lifting the receiver at the speaking station N, the call finder AS is set to the subscriber's N number in the already described manner. When 30 the call finder AS has been duly set, the key T is momentarily pressed, whereby the differential relay X is energized in the same manner.

35 By the closing of contact 29x, relay X causes the energization of relay P over contacts 26t, 27r, 29x, 32p, winding II of relay P, battery, earth. Relay P effects the switching over to the exchange line and the speaking 40 station N is now in a position to comply with the requests of the calling exchange subscriber. The conversation with the required subscriber is initiated in the following method and manner:

45 When the speaking station N has come into communication with the required subscriber, the key T is again depressed, whereby the switching over from the exchange line to the final selector LW is effected in the already described manner. The final selector LW is set to the required subscriber by the speaking station N. When the called subscriber answers and is advised by the speaking station N that he is required by the exchange, the key 50 T at the speaking station N is maintained depressed a somewhat longer period which causes that the call finder AS, over which the speaking station N receiving the exchange connections was connected to the calling ex-

55 change line, is set to contact of the required speaking station marked by the final selector LW. After due setting and upon energization of relay S, relay P is energized which causes the switching over to the exchange line 60 at contacts 18p and 34p. The individual 65

switching operations are the same as described when an enquiry subscriber takes over an exchange conversation.

As will be seen from the above, the final selector LW is utilized as a setting route, 70 while the speaking route for the exchange connection extends over the call finder AS.

Subscribers entitled to various degrees of preference can be accommodated in the system. The setting up of an exchange connection for subscribers not entitled thereto is prevented in each case. The setting up of an exchange connection in an outgoing direction is prevented by the subscriber, for example N2, who is not entitled to connections with the subscribers associated with the exchange not being provided with an earthing key. He is therefore unable to effect the switching-over to the exchange line.

In the case of incoming calls, the setting up of an exchange connection to a subscriber not entitled thereto is prevented by the test circuit of relay S not being established over the c-wiper of the call finder AS and the final selector LW after the subscriber has been marked by the setting of the final selector LW and the call finder AS to the denoted subscriber (by keeping the key T depressed a longer period), as the connection between the contacts of the c-wipers of the call finder 95 AS and the final selector LW is broken for subscribers not entitled hereto at the connecting station 50/51. An enquiry connection during an exchange conversation by the speaking station N or another station entitled to exchange connections setting up connections with a subscriber not entitled to exchange connections is, however, possible as shown in the above, a connection with the subscriber not entitled to exchange connections being set up over the final selector LW.

If a call is received while a conversation is being held, the speaking station N is in the position to listen in to the conversation by throwing over the key MK and to inform the speaking subscriber that an exchange call is awaiting him. The connecting up of the speaking station N during an existing conversation by throwing over the switch MK is effected by shunting the switch wipers a 110 and b of the call finder AS.

Instead of the exchange signalling device AZ taking the form of a bell, a relay may be utilized which connects up a signalling device at the speaking station N and further connects up the induction winding J of a signalling device to the winding S3 by closing contact 52az. Hereby a signal is inductively transmitted over the feeding bridge, and also a speaking subscriber who, in the same manner as already described in the case of the subscriber N, receives an incoming exchange call after the switching over to the exchange line and then switches him over to another subscriber.

In Fig. 2 a sub-exchange device is shown with its main parts the outgoing exchange traffic being effected over the switches of an automatic private exchange while incoming 5 connections are set up by means of plugs and jacks to the individual substations. The devices necessary for the enquiry of the incoming exchange calls have been omitted as they are not necessary for the understanding 10 of the invention and it will be assumed that the operator's position is vacant (for example during the night) in which case the plug St has been inserted in the ordinary jack 2 connecting up a substation N3 which 15 is to set up the incoming exchange connections during the absence of the operator.

The operation of the circuit will now be described in the case of incoming exchange calls.

20 The alternating ringing current transmitted by the exchange periodically energizes the line relay A. By means of its contact 60a this connects up a ringing relay R which, by throwing over contacts 61r and 62r transmits the ringing current to a substation connected to the jack K2 into which the plug St has been inserted. In the substation N3 the test relay P has been connected to battery by the insertion of the plug St and this 30 relay, by means of its contacts 63p and 64p switches through the speaking leads to the substation. The subscriber N3 is guarded in known manner by the short-circuiting of winding II of relay P at the contact 65p.

35 As soon as the plug is inserted into the jack relay P is immediately energized in the shown embodiment. It is, however, possible to make the test relay P effect the switching over of an exchange connection only when such a connection is required, with the consequence that the subscriber N3 will be engaged only when such a call arrives.

40 By the throwing over of contacts 61r and 62r the ringing current will be sent out to 45 the substation N3. If this subscriber lifts his receiver in a ringing pause, relay S is energized, whereas relay X, located in series with relay S, will not be energized as its two windings are differentially connected. 50 A loop to the exchange is formed by means of contact 66s and this loop completes a circuit for the ringing current from the exchange and substation at contacts 68v1 and 69v1. The substation N3 inquires the number 55 wanted by the calling subscriber. In case the calling subscriber wishes to speak to another substation, the substation N3 presses its earthing key momentarily whereby the differential relay X is energized over 60 the winding II to which battery is applied, and by means of its contact 70x energizes relay D which with its contact 71d prepares a locking circuit for itself and also by means of contact 72d prepares the circuit for relay 65 U. When the earthing key is released, relay

X is released and relay D remains energized over contacts 73x and 71d while relay U is energized over: earth, contacts 73x, 72d, winding I of relay U, battery, earth.

The loop to the exchange is maintained over contact 74u and the choke Dr2 while contacts 75u and 76u connect the section of the exchange line which is associated with the substation to an enquiry lead RA. A loop is formed over contact 66s and choke Dr1 which causes that the preselector or call finder is connected up to a group selector or final selector. Station N3 now dials the required substation and notifies the arrival of a call. If the called station does not wish to receive 70 the call or is engaged, the night operating station can release the enquiry connection by a further momentary depression of the earthing key and advise the calling subscriber accordingly.

75 When the earthing key is depressed the second time, relay X is re-energized. Contact 73x breaks the circuit for relay D and winding I of relay U. Relay D releases but a fresh locking circuit for relay U is formed over its winding II and contacts 77u and 70x. When the earthing key is released relay U, due to the release of relay X, releases also and the station N3 is again connected up to 80 the exchange subscriber.

85 If, however, the called substation accepts the exchange call, the subscriber at station N3 presses the earthing key a somewhat longer period (about two or three seconds). Relay X is thus energized during a longer period 90 which causes a thermo relay Th to be heated over: earth, contacts 70x, 77u, thermo relay Th, battery, and closes its contact 78th after a certain period. Hereby a circuit for a relay N will be set up over its winding I parallel to the winding of the thermo relay Th, and over the closed thermo contact 78th. A connection between the exchange line AL and the enquiry line RA is set up by the contacts 95 79n and 80n over two condensers and by means of contact 81n the loop to the exchange is maintained. At contact 82n winding II of relay N forms a bridge between the two lines of the enquiry leads RA which maintains the circuit for the enquiry call. By contact 83n the test circuit for station N3 is broken over relay P which thus releases 100 and disconnects the exchange line at contacts 63p and 64p whereby a listening in to the conversation carried on will be prevented.

105 A condition for this type of maintenance of relay N over winding II is that the system used in the private installation includes a return release, that is to say, that the release is effected by the called subscriber ending the conversation. When the subscriber, therefore, replaces his receiver the circuit for winding II of relay N is broken. The relay releases and its re-energization is prevented 110 by contact 82n being opened. The loop to 115

the exchange is opened by contact $81n$ and the release of the connection thus effected.

The manner of maintaining relay N in the system adopted in the private installation can be effected in various ways. If, for example, the system includes a final selector which has a common feeding for both calling and called subscribers, the circuit for relay N can be set up according to Fig. 3. The two windings of relay N are placed in parallel to the feeding relay of the final selector and maintained over the loops of the called subscriber. When this subscriber has ended the conversation the circuit for relay N is broken and the release thereby effected.

It is assumed in the described examples that only substations entitled to exchange connections are connected up to the automatic private installation. Should this not be the case and there are no private systems entitled to exchange connections, the connecting up of exchange calls over enquiry lines to private systems are prevented by suitable circuit arrangements. In such cases it is recommended that the substations and private stations are split up into various 10 or 100 line groups. If, at the setting up of an enquiry connection the number of the outgoing impulse series is counted by means of a small switch, the unauthorized connections can be prevented according to Fig. 4 in the following manner.

It will be assumed that the substations comprise the numbers 0 to 50 and the private stations 50 to 100. It can be ascertained by means of the first impulse series whether the subscriber called over the enquiry line is entitled to exchange connections or not. The operator at substation N_3 presses his earthing key and effects the switching-over to the enquiry connection RA already described in conjunction with Fig. 2. The required subscriber is then dialled. According to Fig. 4 contact $84s$ of the bridging relay is intermittently de-energized during the impulse series and closes a circuit for the rotary magnet DM of the selector switch over: earth, contacts $84s$, $85u$, the low resistance winding I of the slow acting relay H , switch wiper a , rotary magnet DM , battery. At the first rotary step this circuit is broken by the switch wiper a , but the circuit for relay H and the rotary magnet DM is maintained over the traversed contact segment and contact $86h$. After the first impulse series, the contact $84s$ remains open a somewhat longer period and relay H releases. The rotary magnet DM can no longer be actuated by the succeeding impulse series as contact $86h$ is opened. If the rotary switch now has set its wiper b to a contact which is connected to the heating winding of the thermo contact, the switching over of the connection to the called second subscriber can only be set up by an extended depression of the key as described in the case of Fig. 2.

When relay U releases at the release of the connection the rotary magnet DM is connected to battery over: earth, contacts $87x$, $88u$, $89h$ traversed contact bank, wiper a , rotary magnet DM , battery. At each armature attraction the rotary magnet DM actuates contact $90dm$ over which relay H is energized over winding II . The circuit for the rotary magnet DM is broken by means of contact $89h$, the rotary magnet DM releases and opens its contact $90dm$. Hereby the circuit for relay H is broken etc. With the aid of relay H the rotary switch is thus restored to its original position.

The facility to set up an exchange connection from one substation to another without the intervention by an operator can also be effected in the case of outgoing calls as will be seen from the following description. In order to set up a connection with an outgoing exchange line, the subscriber dials a certain number and the final selector sets the c -lead to a free exchange line. A circuit for the final selector extends over: earth, contact $91n$, relay C of the exchange line, contact $92t$, resistance, 93 , battery, earth. The connecting up of the speaking leads is effected in the final selector in known manner and the relay allocated to the exchange line causes the energization of relay S but not relay X . The slow acting relay T is connected up by contact $93c$ for the purpose of initiating the release.

The first substation then dials the required exchange subscriber in the case of an automatic exchange. The same facilities as in the case of incoming calls are now provided, that is to say, over the enquiry lead RA a second substation can be called and by a somewhat longer depression of the earthing key the switching over of the exchange line to the second substation called over the enquiry lead can be effected. The c -lead is broken by contact $91n$ for the purpose of cutting off the first connection, the final selector is released and the exchange line is simultaneously guarded for the duration of the conversation.

As will be seen from the specification, no alterations are necessary at the substation to enable this station to switch over exchange connections.

The feature of the present invention is not limited only to the described arrangements, but can also be used in the case of engaged substation exchanges when the switching over of an exchange call without an intervening operator is to be effected by another substation.

If the switching over facility is to be provided only in an engaged exchange, it is sufficient in most cases to provide only a small part of the exchange line with the devices necessary for this operator.

By the thermo contact th being heated only in the case of enquiry connections according to Figs. 2 and 4, it is possible to effect another

signal by pressing the earthing key a longer period, in case no enquiry connection is set up, for example, a special signal can be given in this case at the exchange which demands inclusion in the exchange conversation.

What is claimed is:

1. In a telephone system, a local exchange, a trunk extending from a main exchange to said local exchange, a finder connector link at said local exchange for establishing local connections, means for connecting the talking conductors of said trunk to the talking conductors of said link, and means for controlling a portion of said link as a setting route and another portion of said link as a speaking route when incoming connections are set up over said trunk by said main exchange.

2. A system as set forth in claim 1, in which the desired subscriber is denoted by the setting of the connector portion of said link and subsequently the talking connection is set up over the finder portion of said link.

3. A system as set forth in claim 1, characterized by the provision of a station at said local exchange for receiving incoming calls, together with means at said station for controlling the setting and talking connections for said calls.

4. In a telephone system, a local exchange, a trunk extending from a main exchange to said local exchange, a common line in said local exchange which is used for setting up local connections, a station at said local exchange for receiving incoming connections from said main exchange, a switching device at said local exchange controlled by said receiving station for the setting up of incoming connections, said switching device also being controlled by other stations at said local exchange entitled to make connections to said main exchange.

5. In a telephone system, a local exchange, a trunk extending from a main exchange to said local exchange, means for establishing a connection between two subscribers one in each of said exchanges, a switching device at said local exchange, means at the local subscriber's station for operating said switching device to connect the main exchange subscriber to another local subscriber's station, and means for preventing the switching device from connecting up the second mentioned local subscriber's station when said second station is not entitled to connections from the main exchange.

6. In a telephone system, a sub-exchange, a plurality of subscribers, a common trunk line accessible to said subscribers over a common line finder, a common connector controlled by any one of said subscribers over said line finder and common trunk to complete local connections, a trunk line to a main exchange, and a switching device controlled by any one of said subscribers to disconnect said common trunk line from

said connector and to connect said common trunk line to said main exchange trunk.

7. In a telephone system, a sub-exchange, a plurality of subscribers, a common trunk line accessible to said subscribers over a common line finder, a common connector controlled by any one of said subscribers over said line finder and common trunk to complete local connections, a trunk line to a main exchange, a switching device controlled by any one of said subscribers to disconnect said common trunk line from said connector and to connect said common trunk line to said main exchange trunk, and means for disconnecting said main exchange trunk from said common line and for connecting said common line to said connector to complete a connection to a local subscriber without releasing said main exchange connection.

8. In a telephone system, a local exchange, a trunk extending from a main exchange to said local exchange, a station at said local exchange for receiving incoming calls from said main exchange, a finder for connecting said station to said trunk, a called station, a connector linked to said finder and controlled from said first station to select said called station, and means controlled by the subscriber at said first station for starting the re-operation of said finder to connect the called station to said trunk.

In witness whereof, I hereunto subscribe my name this 19th day of August, A. D. 1931.

ADOLF WASCHNACK.
